GATE

Filed July 28, 1928

Henry Spangenberg, Inventor.

By

Geo. W. Ballard, Attorney

UNITED STATES PATENT OFFICE

HENRY SPANGENBERG, OF LONGBRANCH, WASHINGTON.

GATE

Application filed July 28, 1928. Serial No. 295,896.

My invention relates to traffic gates used on farms and estates where vehicle gates are required. It more particularly pertains to double acting gates through which 5 automobiles and other motor driven vehicles are driven. The objects of my invention are, first, to provide a gate that can be opened from either side by the contact and push of an automobile while the driver remains seated within the car; and second, to provide a gate that, when a vehicle has passed through, will automatically close of itself by gravity, and thus save the time and the effort of getting out of the car to open and close the gate.

15 My invention has the further object of providing devices whereby any gate hung in the ordinary manner with hinges, can be rehung and equipped to be opened and automatically closed as hereinafter described.

20 I attain these objects by means of the devices illustrated in the accompanying drawing, in which—

Figure 1 is a side view of an ordinary form of vehicle gate with my newly invented improvements in use thereon; Fig. 2 is a top view of Fig. 1; Fig. 3 is an enlarged top view of the upper hinge of the gate; Fig. 4 is a top view of the lower hinge with an inner view of the part to be attached to the gate; 30 Fig. 5 is a side view of the lower hinge; Fig. 6 is a side and end view of the gate latch; Fig. 7 is an end and face view of the latch catch; Fig. 8 is an end view of the bumper boards looking to the right as shown in Fig. 35 9, which is an enlarged view of the bumper boards designed to unlatch the gate.

Similar characters refer to similar parts in the several views.

Heretofore, various devices have been invented for opening and closing driveway gates by means of cords, chains, pulleys, springs, weights and other mechanisms, all of which are more or less cumbersome and awkward, unsightly and expensive. Some 45 are quite difficult to install and operate.

My new improvements require some simple additions to those used in the making and hanging of an ordinary driveway gate. They do not mar the appearance of the gate 50 and are so practical that the gate cannot get

out of order. The gate can be readily repaired in case of damage. It can be opened as readily by hand as any other gate by one going through on foot or on horseback.

Referring to the drawing, it will be seen 55 that any form of gate 1 as commonly used for driveways may be equipped with my new improvements. The gate is designed to be closed by gravity. To secure this action, the upper hinge is of a common form of stud and socket hinge 2, but the socket member must be so formed that the pivot will be on the central vertical plane of the gate as indicated in Fig. 3. This hinge must be strong and securely fixed, it being the main stay 60 and support of the gate. The lower hinge 3 is made with two pivotal bearings 4-4 as shown in Figs. 4 and 5. The sockets of this hinge are made open in order that they may alternately swing free of their pivotal 65 bearings when the gate is opened back and forth in opposite directions. When the gate is closed, they rest in balanced contact as shown in Fig. 4 from the gravity of the gate. It will be seen the socket member is 70 made adjustable by means of slots 5, whereby it may be centered on the gate by adjusting the bolts 6-6 in the L-shaped hinge straps 7-7. By this means the hinge 3 can be 75 centered and fixed on any thickness of gate and the gate be hung in alignment with the latch catch on the opposite side of the gateway.

The gate latch 8 and the catch 9 are similar to other gate latches in general form. In my improvement the latch 8 is made L-shaped 85 with a sort upright extension 10 with two small holes near its top into which two latch lifting wires 11 are attached. The other end of these wires are separately attached to the ends of the bumper boards 12-12 hinged 90 onto the two sides of the gate and directly opposite each other. The bumper boards are spread apart by an inverted U-shaped brace 13 and fixed between the bumper boards to hold them a suitable distance apart at their outer ends. The bumper boards 12 being hinged on different centers, the spreading member 13 is to be fixed with some looseness to permit the bumpers to swing freely. Each latch lifting wire is to be attached with equal 95 100

tautness to its respective bumper board, so that when the latch 8 is down in the catch 9, the bumper boards will extend equally distant from the sides of the gate as shown in Figs. 2 and 9.

- 5 There is no uncommon method required in constructing a gate and attaching my improvements thereto. All can be done in a simple and practical manner as indicated by the drawing and as herein described.
- 10 To open the gate we will consider an automobile is approaching from the farther side of Fig. 1. The driver slows down as he comes to the gate so that the car wheel or bumper will contact the board 12 with a mild bump 15 pushing it toward the body of the gate. The opposite board 12 will be pushed from the gate as indicated in Fig. 2, whereby its latch lifting wire 11 will be given a quick jerk that 20 will lift the latch 8 from the catch 9 and the gate will swing open as the car pushes through the gateway. The farther open socket of the lower hinge 3 swings clear while the near socket carries the gate resting thereon. The outer end of the gate is thus slightly 25 lifted and gravity will promptly swing it back to the latch as soon as the car passes through and sets the gate free. The gate may move swiftly when it comes to the latch 30 and, to prevent injury, the latch catch is slightly beveled at the top of the notch. This will allow the latch to skip over the catch, thus letting the gate swing or rock back and forth on the double bearings 4-4 of the lower 35 hinge 3 till the latch finally catches in the notch. It will be observed this automatic action of the gate is caused by gravity. It will also be observed the opening of the gate and the closing of the same will be the same 40 when a car approaches from the front side of the gate.

It will be seen that my improvements in gates as shown and herein described, are simple, practical and economical in construction and will be useful in gateways on farms, estates and elsewhere where automotive vehicles are used.

It is to be observed that should the gate posts be round as is often the case on farms, 50 the latch catch 9 and the hinge 3 can be fitted to plane faces cut into the side of each post. Each post can be securely braced and stayed by the adjoining fence and otherwise so that each will stand plumb and true after the gate 55 is hung in place.

A footman can open the gate by lifting the latch by hand or by kick or quick push of the foot on one of the bumper boards.

Having described my invention, I claim:—
60 The combination with a double acting gate, of a pivoted gravity latch with an upright extension at its pivoted end, bumper boards hinged on the opposite sides of said gate, a fixed spreader between said bumper boards, 65 and uniform means for attaching the ends of

said bumper boards with the upright extension of said gravity latch whereby each of said bumper boards is held at the same angle with its respective side of said gate when said gate is shut, as set forth and described.

HENRY SPANGENBERG.
